UNITED STATES PATENT OFFICE.

HENRY S. MAGEL, OF SIDNEY, IOWA.

FOLDING TUB RACK.

Application filed December 26, 1922. Serial No. 698,931.

To all whom it may concern:

Be it known that I, HENRY S. MAGEL, a citizen of the United States, residing at Sidney, in the county of Fremont and State of Iowa, have invented certain new and useful Improvements in Folding Tub Racks, of which the following is a specification.

My invention relates to benches or racks for supporting wash-tubs and the like. It is the object of my invention to provide a simple, inexpensive and convenient support for a washtub or like article, adapted to sustain the same at a height suitable for use, and to enable the tub while mounted upon the support to be readily moved about upon a floor, regardless of the weight of the tub-contents. A further object of my invention is to provide a support of this character which may be readily folded so as to occupy a small space when not in use, which is securely retained in its extended form, and in which the securing means are easily releasable when the device is to be collapsed or folded.

In the accompanying drawings Fig. 1 is a perspective view of a device embodying my invention, Fig. 2 is a detail vertical section and partial side elevation showing one of the brace-rod connections, Fig. 3 is a plan view of the device, Fig. 4 is a side view thereof, and Fig. 5 is a detail section on the line 5—5 of Fig. 2.

In the illustrated embodiment of my invention I provide a main frame consisting of a pair of vertical side-pieces 6, and the upper and lower cross-pieces 7 and 8. Said cross-pieces are arranged vertically edge-wise, and the ends thereof are secured in vertical notches or mortices in the upper and lower ends of the side-pieces 6. At their upper ends said side-pieces extend slightly above the upper edge of the cross-piece 7, and the inner edges of the projecting portions are preferably beveled as shown. To said main frame there is hinged at each side a swinging or folding frame, comprising a vertical side-piece 9 of the same shape as the side-pieces 6 of the main frame, and horizontal upper and lower pieces 10 and 11, which are secured in notches in the upper and lower ends of said side-piece 9. To the sides of the pieces 10 and 11, at the inner ends thereof, are secured the hinges 12, said hinges being also secured to blocks 13 which are attached to the sides of the upper and lower cross-pieces 7 and 8 of the main frame,

near the center thereof. Said blocks 13 are oppositely offset from the center of the main frame at the two sides thereof, so that when the swinging frames are in their extended positions, at right angles with the main frame as shown in Fig. 3, they will be aligned with each other, and the four side-pieces 6 and 9 will be symmetrically positioned about a vertical axis passing through the center of the main frame. From said extended positions the hinged frames are swingable about the vertical axes of the hinges 12 to the positions shown by dotted lines in Fig. 3, at which the edges of the members 9 engage the sides of the cross-pieces 7 and 8 adjacent to the members 6.

Releasable bracing means are provided for holding the hinged or swinging members in the extended positions. In the preferred structure, each of the members 9 is provided at the inner side with a pair of angle-brackets 14 having openings in which is pivotally held the vertical central portion 15 of a U-shaped rod, said rod having horizontal upper and lower portions 16 and 17, each with short terminal portions 18, turned upwardly and downwardly, respectively. Said terminal portions 18 extend into T-slots formed by metal channel-members 19 which are secured to the upper edges of the lower cross-piece 8 and to the lower edges of the upper cross-piece 7, adjacent to the outer ends thereof. The channel-members 19 are made of sheet-metal and are secured to said cross-pieces of the main frame by means of flat bars 20 which fit into the channels at the backs thereof, opposite the open longitudinal slots in which the rod-terminals 18 are slidable, said bars 20 being secured to the cross-pieces by means of screws 21. The rod-terminals 18 are each provided with a cross-pin 22, so arranged as to extend beneath the inwardly turned flanges of the channel-members and thereby serve to prevent withdrawal of the terminals from the T-slots formed by the channels. The U-shaped brace-rods are slightly resilient, being so formed that the ends or terminals 18 are pressed yieldingly toward and against the bars 20, and each of said bars is provided with an opening, adjacent to the outer end thereof, adapted to receive the respective end of the brace-rod when the same is in the position assumed when the swinging frames are extended, or at right angles to the main frame. By reason of the resilience

of the brace-rods, whereby the terminals 18 are constantly pressed toward the bars 20, when the swinging frame-portions are moved to their extended positions the rod-terminals enter the holes in the bars 20 and remain seated therein, so that the entire device is thereby held rigidly in the extended position. When the rack is to be folded, the rod-terminals are disengaged from the holes by springing the upper and lower horizontal portions 16 and 17 toward each other, excessive movement thereof being prevented by the engagement of the cross-pins 22 with the channel-flanges. The most convenient way of so springing the brace-rods is by grasping the middle part of the vertical portion 15, between the angle-brackets 14, and pressing said part of the rod toward the side-piece 9, so that the rod is bowed as indicated by dotted lines in Fig. 2. The bowing of the central part of the brace-rods lifts the lower portions 17 and lowers the upper horizontal portions 16, so that the terminals 18 are disengaged from the bars 20, and said terminals 18 may then slide inward along the slots in the channel-members 19 as the swinging frames are turned in against the sides of the main frame.

The entire device is preferably mounted upon castor-wheels so as to be easily moved about upon a floor, the castor-wheels 23 being arranged beneath the outer end-portions of the lower cross-pieces 8 and 11, as shown. The rack is so proportioned that a tub or the like may rest upon the skeleton support formed by the upper edges of the cross-pieces 7 and 10, being thus supported at four points in the same plane, and being prevented from slipping off the rack, by reason of the upper end-portions of the side-pieces 6 and 9, which extend above the cross-pieces. Thus, when it is desired to move the rack and tub, the user may push directly upon the tub in the desired direction of movement, without liability of thereby displacing the tub from the support.

Now, having described my invention,

what I claim and desire to secure by Letters Patent is:

1. A device of the class described, comprising a main frame having vertical side-pieces and horizontal upper and lower cross-pieces connecting said side-pieces, swinging frames each having a vertical side-piece and horizontal upper and lower pieces secured to said side-piece, hinges connecting the ends of said upper and lower horizontal pieces with intermediate portions of the corresponding cross-pieces of the main frame at opposite sides thereof, guide-channels on the cross-pieces of the main frame, brace-rods mounted pivotally upon said swinging frames and having end-portions slidably engaging said guide-channels, and members associated with said guide-channels and engageable by the ends of said brace-rods to retain the swinging frames in fixed relation to the main frame.

2. In a device of the class described, a substantially rectangular main frame having vertical side-pieces and upper and lower cross-pieces, swinging frames hinged to the sides of the main frame, each swinging frame comprising a vertical side-piece and an upper and lower horizontal piece, the ends of the latter being hinge-connected with the sides of the main-frame cross-pieces and thereby held in horizontal alignment with the same, guide-channels secured on the adjacent edges of the main-frame cross-pieces, U-shaped brace-rods having vertical intermediate portions pivotally connected with the side-pieces of the swinging frames and horizontal portions extending to the guide-channels, and means associated with the guide-channels for receiving the ends of the brace-rods to retain the swinging frames in extended position relative to the main frame, the ends of the brace-rods being normally pressed toward said retaining means and being releasable therefrom by bowing of said vertical intermediate portions of the rods.

HENRY S. MAGEL.
